UNITED STATES PATENT OFFICE.

JAMES D. FRARY, OF NEW BRITAIN, CONNECTICUT.

DESIGN FOR KNIFE-HANDLE.

Specification forming part of Design No. 7,002, dated November 25, 1873; application filed November 13, 1873.
[Term of Patent 7 years.]

To all whom it may concern:

Be it known that I, JAMES D. FRARY, of New Britain, in the county of Hartford and State of Connecticut; have invented a new Design for Cutlery Handle; and do hereby declare the following, when taken in connection with the accompanying drawing and the letters of reference marked thereon, to be a full, clear, and exact description of the same, and which said drawing constitutes a part of this specification, and represents a side view of a knife.

This invention relates to a design for the bolster and tip of handles of table cutlery; and it consists in the configuration of the bolster and tip together, or separately, whereby on one or both appears an inlaid acorn.

I represents a knife with the new design for handle, but it will be understood that the same

design applies to other articles of table cutlery.

A is the bolster; B, the tip, which have in their surface an ornament in the form of an acorn, pointing toward the two extremes, the base of the acorn toward the covered part or scale of the handle.

In some cases the tip B is not used, and in others the tip only, with a bolster of different construction. I therefore do not confine myself to the use of the two in combination, but together or separately.

I claim as my invention—

The design for cutlery handle, as herein described and shown in the accompanying illustration.

Witnesses: JAMES D. FRARY.
